UNITED STATES PATENT OFFICE

ERIKS TACKER, OF KIEL, GERMANY, ASSIGNOR TO FRIED. KRUPP AGRIENGESELLSCHAFT GERMANIAWERFT, OF KIEL-GAARDEN, GERMANY.

SUBMARINE BOAT

1,531,310.

Specification of Letters Patent. Patented Dec. 15, 1914.

Application filed May 23, 1914. Serial No. 811,658.

Field whom it may concern:

Be it known that I, HANS TACKER, a citizen of the German Empire, residing at Kiel, Germany, have invented certain new and useful Improvements in Submarine Boats, of which the following is a specification.

This invention relates to submarine boats, which are driven while traveling on the surface of the water by one kind of engine and while traveling under the surface of the water by another kind of engine, as for example, by an internal combustion engine and by an electromotor, and the object of the invention is to provide means which will enable an engine plant of as high a capacity as can possibly be obtained with the space available in the submarine boat.

According to the invention this end is attained in the following way. In contradistinction to submarine boats as hitherto known, and in which both the internal combustion engine and the electromotor drive directly on to the propeller shaft, the internal combustion engine drives direct on to the shaft but the electromotor drives through the interposition of a gear wheel or chain gearing or the like and if necessary through a suitable transmission.

The subject matter of the invention is shown in the way of example in the drawing to which reference is made.

Figure 1 is a vertical longitudinal section through the part of the boat which holds the engine plant. Figs. 2 and 3 are vertical sections through the pressure-proof inner hull of the boat on the lines 2-2 and 3-3 respectively of Fig. 1 looking forward from the front, while Fig. 4 is a section, corresponding to Fig. 2 and shows a somewhat different constructional form of the subject matter of the invention.

The constructional form shown in Figs. 1-4 will be fully described first. A is the outer hull, B the pressure-proof inner hull, C the propeller shaft, D the boat while the boat is traveling on the surface of the water is driven by an internal combustion engine D, but when the boat is traveling under the surface of the water, by an electromotor E through the medium of a gear or chain gearing F, G, H.

According to the invention the propeller shaft C is set, irrespective of the size of the engine, at the same height in the engine compartment, as to the crank of the internal combustion engine D.

internal combustion engine D will permit, (see Fig. 2). With this arrangement the height of the space available inside the pressure-proof inner hull B can be completely utilized and the engines can consequently for a prescribed number of revolutions attain the highest efficiency it is possible to acquire under the conditions of space. The electromotor E is on the contrary not placed directly on the shaft C but at some other suitable point of the engine room, which may conveniently be, as shown in Fig. 1, above the thrust bearing K for example. By this arrangement the additional advantage is secured that the engine room may be made shorter than is possible with the usual arrangement of the electromotor and thrust bearing one behind the other.

Since the electromotor is no longer arranged directly on the propeller shaft, there is also the advantage that the electromotor may be given a greater number of revolutions and by means of a suitable transmitting gearing be allowed to drive from a high speed down to a low speed on to the propeller shaft whereby again the size of the electromotor is considerably reduced. A constructional form of this kind is shown in Fig. 4, in which the pinion L mounted upon the shaft of the electromotor transmits motion to the gear wheel M carried on the propeller shaft C. In other respects this constructional form corresponds with that illustrated in Fig. 3.

The invention is obviously not limited to the use of an internal combustion engine and an electromotor, but is generally applicable in all those cases where the use of two engines of any desired kind for the driving of submarine boats is concerned, and of which one permits of the shaft being set lower down than does the other.

I claim:

1. In a submarine boat a driving shaft, two separate engines acting upon said shaft while the boat is traveling on the surface of the water or under water respectively, one of said engines being mounted on the level of said driving shaft directly on to said shaft, the other engine being mounted on a shaft and driving on to the latter indirectly.

2. In a submarine boat a driving shaft, an internal combustion engine and an electromotor both acting upon said shaft while the

the boat is traveling on the surface of the water or under water respectively, said internal combustion engine being mounted on the level of and driving directly on to said

5 shaft, said electromotor being mounted above said shaft and driving on to the latter indirectly.

3. In a submarine boat a driving shaft, an internal combustion engine and an elec-
10 tromotor both acting upon said shaft while the boat is traveling on the surface of the water or under water respectively, said internal combustion engine being mounted on

the level of and driving directly on to said shaft, said electromotor being mounted 15 above said shaft and driving on to the latter indirectly, a suitable transmission gearing between said electromotor and said shaft.

In testimony whereof the foregoing specification is signed in the presence of two wit- 20 nesses.

HANS TECHEL.
